HORIZONTALLY ADJUSTABLE VENETIAN BLIND

Nathan Edward Moore, Jr., Greensboro, N. C.

Application March 26, 1956, Serial No. 573,816

15 Claims. (Cl. 160—168)

The present invention relates to adjustable closures of the multiple louver Venetian blind type and relates more particularly to improvements in Venetian blinds in which the entire closure may be adjusted widthwise within limits.

Normally louver closures of the Venetian blind type are custom built to specific specifications both in length and in width corresponding to the window or recess frame in which the blind will be suspended. Mismeasurement in oversizing blind widths necessitates time consuming material removal from the ends of each blind slat. Also some material must be removed from the width of the tilt bar, the channel box and the bottom rail of each blind before the complete blind may be mounted in place.

In view of the many window widths, standard as well as special, customarily found in a single home or apartment, equipping all of the windows entails blinds of various widths. Retail establishments desiring to merchandise Venetian blinds are obliged to invest in large inventories in order to stock blinds of the many different widths so as to have them available for immediate sale.

Therefore, an object of the present invention is the provision of a width-adjustable Venetian blind which is freely extendable between limits.

Another object of this invention is to provide a Venetian blind in which the individual slats have overlapping portions which reach between supporting ladder tapes and the slats are extendable widthwise.

Yet another object of the present invention is the provision of an extensible Venetian blind in which each slat is compounded or articulated with two slat portions that are slidably movable relative to each other and supported between a pair of ladder tapes with a single slat thickness extending beyond the end of each side of the blind and an overlapping intermediate section of the slat portions between the tapes with the inner end of each slat concealed behind opposite ladder tapes.

A further object of the present invention is to provide a width adjustable Venetian blind in which longitudinal manipulation of the top channel will correspondingly vary the overall width of the tilt bar and the ladder slat supporting tapes from which repositioning the individual louver slats may be readily aligned.

Yet a further object of the present invention is the provision of a multiple-tape Venetian blind suitable for expansion between extensive varying widths.

Still another object of this invention is the provision of a Venetian blind which is extensible in width with the individual louver members extending at opposite ends in single thickness beyond supporting ladder tapes with the other ends of the louver members fastened to transverse ladder members and concealed by the ladder tapes.

A further object of the invention is to provide a Venetian blind that is extensible over a large expanse by utilizing a compound louver in which the individual

2

louver members have a single thickness at the terminal ends of the blind and the intermediate portion between louver supporting tapes has a double thickness of the louver and the length of the double thickness portion will vary depending upon the width of opening on which the blind is suspended.

A still further object of the present invention is to provide a variable width Venetian blind in which the intermediate portion of the blind is provided with a double thickness of slat members suitably fastened to prevent objectionable slat sagging and so constructed as to conceal the overlapping slats as much as possible.

Other and further objects and many of the attendant advantages of this invention will become more readily apparent as the invention becomes better understood from the following detailed description taken in conjunction with the accompanying drawings in which like characters of reference designate corresponding parts throughout the several views and wherein:

20 Fig. 1 is a perspective view, with portions removed, illustrating one form of an adjustable Venetian blind of the present invention employing the use of a single pair of spaced louver supporting ladder tapes;

25 Figs. 2, 3, and 4 are enlarged partial perspective views of a portion of a compound slat with a ladder type illustrating various means for securing the compound slat for size adjustment;

30 Fig. 5 is an enlarged partial perspective view of a compound slat and a slat keeper and aligning means;

Fig. 6 is an enlarged perspective view of the tilt bar of Fig. 1 with a portion omitted;

35 Fig. 7 is a perspective view with portions removed illustrating a modified Venetian blind of the present invention incorporating the use of double ladder tapes for supporting compounded slats for increased extensibility;

Fig. 8 is an enlarged perspective view of an adjustable tilt bar with portions removed illustrating the form of tilt bar employed in the embodiment illustrated in Fig. 7;

40 Fig. 9 is an enlarged perspective view illustrating one form of ladder tape supporting drum.

Referring to the drawing and particularly to Fig. 1 there is broadly shown a width adjustable louver enclosure 10, popularly referred to as a Venetian blind, in which the horizontal slats or louver members 11 are supported on the ladder tapes 12 and 13 that are individually connected at the top of the blind to the extensible tilt bar 14 which is pivotally supported in the top extensible channel enclosure 15 and at the bottom to the bottom rail member 16. Suitable slat raising and lowering means are provided for the slats in the form of the lifting cords 17 and lift locking mechanism 18. Tilting of the individual slats 11 to dispose the slats to the desired angular position is accomplished by means of the pivotal action of the tilt bar 14 which is actuated manually through the flexible tilt bar operating cords 19 and 20 and the tilt bar operating mechanism 21 mounted at the right end of the top channel in Fig. 1.

Each individual slat of the series forming the blind is 60 constituted by a compound member formed with two elements: a left portion 23 and a right portion 24, each of which portions has substantially identical cross-sectional areas that are preferably arcuate to enable one slat element to nest in overlapping relation within the other complementing portion. The lengths of the individual slat elements 23 and 24 are equal, and the slat element 23 extends from the right ladder tape 13 to the left margin of the blind. The other slat element 24 of a compound louver slat extends from the left ladder tape 12 to the right margin of the blind. As is clearly illustrated in Fig. 1, somewhat in exaggerated form, the end or overhanging portions of each compound slat is

constituted by single thickness which extends beyond the ladder tapes with the intermediate portion of each slat ladder overlapping each other in a compact manner and forming a double thickness.

To overcome any possible objection to the appearance of an exposed slat end appearing across the horizontal slat reach, the inner ends of each slat are suitably concealed by being secured to one of the split transverse ladder tape members or rungs 25 or 26 which are fastened to and extend between the vertical reaches of each ladder tape 12 and 13. Obviously the right slat element 24 may be fastened at the left to the left tape transverse member 25 with the right portion of the slat passing under the right tape transverse member 25 and extending to the right margin of the blind. The left element 23 will be fastened to the right tape transverse member 26, below the right element 24 and the transverse member 25, with the left portion of the element 23 resting on the top of the left tape transverse element 26 and below the fastened end of the right element 24. By securing each element of a compound slat in a similar manner the slat elements may slide longitudinally over each other in the intermediate portion with the fastened ends remaining virtually concealed behind the ladder tapes. The slat sections may be supported against falling upon pivoting the tilt bar 14 to a suitable angle when the blind is closed by having the slat members constrained from transverse displacement by either fastening the top right slat element 24 at the left to the transverse member 25 as well as the constraining action exerted by the transverse element 25 on top of the element 24 at the right tape member 13.

As the greater portion of the Venetian blinds being sold are either made of aluminum or a steel slat variety, the structure will be so described as having either aluminum or steel slats, however, it is contemplated that with some insubstantial modifications the inventive concept may be equally applicable to wood or plastic slats. One means for securing the inner ends of the slat members to a transverse tape member is to provide a reverse bend 27 in the terminal end portion of the slat. This reverse bend is preferably formed in each individual slat either prior to or during fabrication of the blind and a final crimping operation will securely fasten the reverse bend to a transverse member such as 25. It will be apparent that this reverse bend is preferably formed to return above the slat portion for the right element 24 and below for the left element 23 in order to permit the individual elements to be contiguous.

In Fig. 2 there is illustrated a modified means for fastening the individual portions 23 and 24 to a transverse ladder member 25 by providing the terminal portions of each slat element with a split tape fastening slot 29. The tape fastening slot is formed with openings 30 and 31 spaced apart by the intermediate tabs 32 which are integrally formed in the slat so that each tab may be raised or lowered slightly transversely to the slat to insert a transverse member 25 or 26 therein. It is preferred that the width of each of the openings 30 and 31 is slightly greater than the width of the transverse tape members 25 and 26 in order to prevent an edge of the transverse member from being aligned with the split between the tabs 32 thereby eliminating possibilities of disengagement.

A further modified means for securing the slat portions to the transverse tape members 25 and 26 is by providing a suitable staple 35 which may be inserted to clamp a transverse tape member to an end of a slat member as shown in Fig. 4. It has been found desirable in some applications to employ the use of a metal clamp 36, shown more clearly in Fig. 5 for installation at each transverse member connecting position in order to maintain the individual slat members in constant alignment without impairing the extensible features of the members 23 and 24. The clamp 36 is provided with a contour

substantially similar to the slat cross-section with the terminal portions 37 turned inwardly to engage the slat edges in order to maintain slat alignment. Each clamp 36 may be made so as to fit conveniently on a transverse tape to facilitate installation of the clamps at convenient positions on each slat at the terminal portions so as to conceal the clamp from view behind the vertical reach of the ladder tape.

The top ends of each vertical slat supporting ladder tape 12 and 13 are clamped to a supporting drum 40 that is mounted on one of the telescoping rod sections 41 or 42 of the tilt bar 14. The tilt bar 14 may be provided with longitudinal keyways 43 and 44 in the rod sections 41 and 42, respectively, to receive and guide a supporting drum 40 therein. Relative rotation of the rod sections is reduced due to the locking connection between the base of the supporting drum 40 against the edges of the opening 40a in the section 41. One end of the rod section 41 is supported within the opening 45 in the channel tilt bar supporting plate 46 and the other end of the tilt bar section 42 is supported in the channel tilt bar supporting plate 47 by means of the tilt bar operating mechanism 48 which may be of conventional form. Suitable fastening means (not shown) may be applied to the tilt bar ends to prevent the tilt bar from being separated from the tilt bar supporting plates 46 and 47.

As more clearly depicted in Fig. 6, the left tape securing drum 40 is mounted to the inner rod section 42 through the elongated opening 49 in the outer rod section 41. The right tape securing drum 40 is fastened to the outer rod section in spaced longitudinal relation to the left drum. It will be quite evident that as the tilt bar is extended the tape supporting drums will approach each other and conversely as the rod sections are shortened the drums will move away from each other.

The top channel 15 for enclosing the tilt bar 14 is preferably made extensible longitudinally by having the portions slideable with each other with the section 15a slidably receivable into the section 15b. Expansion or contraction of the tilt bar 14 may be correlated with expansion and contraction of the channel 15. The channel bases 51 are provided with spaced tape openings 52 adjacent to the free end of each channel. Additional spaced elongated tape openings 53 are furnished adjacent to the tilt bar supporting ends of the channels to allow for the longitudinal movement of the tapes 12 and 13 as the blind is adjusted to the required width.

Upon adjusting the width of the blind the tape 13 and right drum 40 will move to the left with the tape 13 which passes through the opening 52 being able to pass unobstructed through the elongated opening 53 in movement to the left. Similarly tape 12 and the left drum 40 may be moved to the right with the tape 12 passing through opening 52 in the channel base 51 of section 15b and the openings 53 in section 15a which are elongated sufficiently to permit lateral movement of the tape 12 to the right or left.

The bottom rail member 16, constituted by the sections 16a and 16b, telescopes longitudinally making the rail adjustable. Ladder tapes 12 and 13 are secured about the bottom of the rail with a suitable fastening means so as to permit the sections to telescope within each other and also to permit the tapes to be displaced along the bottom rail for alignment with the ladder tape fastening drums 40 mounted on the tilt bar 41 enabling the ladder tapes to be maintained in parallel relationship.

Raising and lowering the bottom rail 16 and the slats is accomplished by means of the lifting cords 17 which reach through the conventional lift locking means 18 and through the guide pulley 65 supported in the channel plate 45 and extend to the guide means 56 and 57 that are supported on the bottom part of the drums 40 on the tilt bar. The lifting cords 17 extend in separate reaches to the bottom rail 16 along the inner face of the vertical reach of the ladder tapes 12 and 13 and adjacent to one

edge of the slat members. By extending along the ladder tapes adjacent to the interior side it is possible to eliminate the necessity of notching the individual slats. The cords 17 fit conveniently between the split transverse ladder members 25 and 26 which members restrict the vertical cord reaches from shifting laterally. The lower rail-engaging ends of lift cord 17 are fastened to the bottom rail in the elongated openings 58 that are provided in the bottom rail to allow for the telescopic action of the individual bottom rail sections 16a and 16b during adjustment of the blind to a requisite width.

A modification of the present invention appears in Figs. 7 and 8 wherein there is illustrated in Fig. 7 a Venetian blind capable of being expanded or contracted between rather extensive widths. In this form the individual slats 70, compounded with two sections, a left section 71 and a right section 72 supply the requisite flexibility in width for the blind. Two pairs of ladder tapes 73, 74 and 75 and 76 are furnished to support the slat members in position. The left slat section 71 is supported in a conventional manner at the left to project from the single transverse tape member 77 and extends between the double transverse member 78 on tape 75 to be secured to the bottom transverse member of the double transverse tape members 78 on the tape 74, under the horizontal reach of the slat member 72. The slat 72 extends from right to left and is supported on the ladder tape 76 in the conventional manner to overhang to the right. Extending to the left, slat 72 overlaps the right portion of slat 71 and extends between the double transverse tape members 78 on the tape 74 and is secured to the top double transverse tape member 78 on tape 75. Each of the sections 71 and 72 is provided with a lift cord receiving slot 79 through which the lift cords 80 may be passed so as to be fastened in a known manner to the telescoping bottom rail member 81. A lift cord locking device 82 through which the lifting cords 80 pass is supported by the end plate 83 supported in the top box or channel 84.

A tilt bar 85 is pivotably supported within the top channel 84 by means of the end plates 83 and 86. Tilting mechanism 87 of conventional form is supported on the plate 86 for operation by the tilting cords 88 which reach between the plates 83 and 86 to pivot the tubular telescoping tilt bar 85. The outer sleeve member 89 of the tilt bar is secured at the right end of the channel to plate 83 and reaches a substantial distance toward plate 86. An intermediate portion 91 of the outer tube 89 is removed to expose the inner tube 90 to which is connected the tape clamping drum 92 from which the ladder tape 74 is suspended. Spaced axially from the tape clamping drum 92 which is mounted on the inner tube 90 is a corresponding drum 93 that is fastened to the other sleeve member 89 to which is connected the ladder tape 75. Two other tape supporting drums 94 and 95 are fastened adjacent to the ends of the telescoping tilt bar 85 with the drum 94 being affixed to the inner tube member 90 and drum 95 being affixed to the outer sleeve member 89. As is more clearly shown in Fig. 8 which illustrates the left portion of the tilt bar 85 the drums 92 and 94 are illustrated as being affixed to the inner tube 90 and movable therewith in fixed axial relationship. Relative rotation of the sleeve member 89 and tube member 90 is prevented in the manner as described above by connection of the drum 92 to the inner member 90 through the opening in member 89.

The bases 96 of each of the top box channel portions 84a and 84b are provided with elongated openings 97 through which the tapes 74 and 75 may pass transversely during expansion or contraction of the top channel. The individual channel sections are also provided with elongated openings 98 at each end through which the stationary tapes may pass.

To facilitate lifting of the bottom rail 81 and any number of the other horizontal slats, the lifting cords 80 are

threaded through an opening in the end plate 83 for guided support on the guide roller 100 with individual reaches of the lifting cords 80 extending to swivel guide pulleys 101 and 102 mounted to the tape supporting drums 94 and 95. In Fig. 9 there is illustrated one means for attaching a guide pulley 101 to a tape fastening drum 95. The guide roller 101 is freely supported from the tape fastening drum by means of the pulley bracket 103 so as to avoid interference during tilting action of the tilt bar with the ladder tapes.

The bottom rail 81 is supported to the blind by means of the ladder tapes which are secured in a suitable manner to the bottom of the rail member. The end tapes 73 and 76 are securely fastened in position, with the tapes 74 and 75 being free to be displaced relatively along the base rail member.

In operation, for modifying the width of the blind it is only necessary to expand the top channel 84 which in turn will elongate the tilt bar 85 with the tape fastening drums 92 and 94 being displaced to the left on the inner tube section 90 and the drums 93 and 95 on the outer sleeve member 89 being displaced to the right. The distance between the tapes 74 and 75 will be diminished as the tapes approach one another as the overall width of the blind is increased. It is this intermediate portion only which will have the overlapping double thickness of the slats. Clamps 36, not shown in this embodiment, similar to those described above in the first described embodiment, may be used where desirable.

It will be readily apparent that the clamping means employed for retaining the inner ends of the slat members such as shown by the fastening openings 105 are substantially the same as those shown and described for Fig. 2, however, other fastening means may be employed. When the Venetian blind top channel is extended the bottom rail member 81 may be telescoped outwardly in order to expand the tapes at the bottom permitting the tapes to be arranged in parallel relation.

Obviously many modifications and variations may be made in the construction and arrangement of the fastening means as well as the position of the various tape clamping means on the tilt bar as well as modifications made to the top channel box and the bottom rail in the light of the above teachings without departing from the real purpose and spirit of this invention of expanding individual louver slat members. It is, therefore, to be understood that within the scope of the appended claims many modified forms of the present inventive concept as well as the use of alternatives and mechanical equivalents may be reasonably included and modifications are contemplated.

What is claimed is:

1. An adjustable Venetian blind comprising an extensible top channel, an extensible tilting bar pivotally supported in the top channel, a pair of ladder tape clamping means axially spaced from each other on said tilting bar, said clamping means being movable toward each other as the top channel is extended, and away from each other as the channel is contracted longitudinally, a pair of ladder tapes spaced apart and extending from said clamping means at one end, said ladder tapes having double transverse slat supporting elements, an extensible bottom rail supported at the other end of the tapes, a series of horizontal compound louver slat members supported on the slat supporting elements, each of said slat members having one end reaching beyond a tape and one portion reaching between the pair of tapes, the slat reach extending between tapes forming an overlapping portion, each of said slat members of a single compound slat being fastened adjacent to the other end to a transverse element on opposite tapes, in overlapping sliding relation, means for pivoting the tilting bar and tape clamping means, and means for raising and lowering the bottom rail and other slats in successive order upwardly from the bottom rail.

2. An adjustable Venetian blind enclosure comprising a telescoping top channel, a telescoping tilt bar pivotally supported in said channel, said tilt bar having sections slidable in each other, a pair of ladder tape clamping means axially spaced from each other, one tape clamping means on each slidable section, said clamping means being movable toward each other as the top channel is extended, and away from each other as the channel is contracted longitudinally, a pair of ladder tapes spaced horizontally from each other and extending from said clamping means at one end, said latter tapes having transverse slat supporting elements, a telescoping bottom rail supported at the other end of the tapes, a series of horizontal compound slat members supported on the slat supporting elements, each of said slat members having one end reaching beyond a tape and one portion reaching between the pair of tapes, the slat reach extending between tapes forming an overlapping portion, each of said slat members of a single compound slat being fastened adjacent to the other end to a transverse element on opposite tapes, in overlapping relation, the end fastened to a transverse element being concealed by a ladder tape, means mounted on the channel for pivoting the tilt bar and tape clamping means, and means for raising and lowering the bottom rail and other slats in successive order upwardly from the bottom rail.

3. An adjustable Venetian blind comprising a top channel, an extensible tilting bar pivotally supported in the channel, a pair of ladder tape clamping means axially spaced from each other on said tilting bar, said clamping means being movable toward each other as the tilting bar is extended, and away from each other as the channel is contracted longitudinally, a ladder tape extending from each of said clamping means at one end, said ladder tapes having transverse slat supporting elements, a bottom rail supported at the other end of the ladder tapes, a series of horizontal compound slats supported on the slat supporting elements, each of said slats having one end reaching beyond a ladder tape and one portion reaching between the pair of ladder tapes, the slat reach extending between tapes forming a double slat thickness, each of said slats of a single compound slat being fastened adjacent to the other end to a transverse element on opposite tapes, in overlapping sliding relation, means mounted in the channel for pivoting the tilting bar and tape clamping means, and means for raising and lowering the bottom rail and other slats in successive order.

4. An adjustable Venetian blind comprising an extensible top channel, an extensible tilting bar pivotally supported in the channel, an extensible bottom rail, a pair of vertically reaching ladder tapes laterally spaced from each other, said tapes having vertically spaced slat supporting transverse members fastened to the tapes, said tapes connected at one end to the tilt bar and at the other end to the bottom rail, a series of articulated slats supported on the transverse members, each articulated slat reaching from one tape laterally beyond the opposite tape, the reach between tapes having overlapping slat portions and a single slat thickness extending beyond each tape, means for pivoting the tilting bar, and lifting means for raising and lowering the bottom rail and the louver slats.

5. A widthwise adjustable Venetian blind comprising a telescoping top enclosure, a telescoping tilting bar mounted for pivotal movement in the top enclosure and extensible therewith, a telescoping bottom rail, spaced apart vertically reaching ladder tapes extending between the tilt bar and the bottom rail and fastened thereto, tape fastening means on the tilt bar receiving one end of the tapes, the other end of the tapes being fastened to support the bottom rail, each of said tapes having vertically spaced transverse members, a series of horizontal compound slat members spaced vertically on the

transverse tape members, each of said compound slat members having two portions, each of said slat portions reaching only a portion of blind overall width, an opposite end of each slat portion fastened to a transverse member, the slat reach between tapes having a double thickness constituted by the two slat portions and an end of each slat portion projecting with a single thickness at one end beyond a ladder tape, said slats being slidable relative to each other as the ladder tapes are separated or brought closer together.

6. A Venetian blind comprising an extensible head channel, a telescoping tilting bar in said channel supported for oscillatory movement, means connected to the tilting bar for oscillating the bar, spaced apart ladder tapes each having connecting rungs, said tapes being connected for suspension from the tilting bar, a series of vertically spaced apart compound slat members supported on the rungs, each of said slat members being articulated with at least two slat reaches, one portion of each slat reach extending between the spaced apart tapes in overlapping relation and the other reach of each slat extending beyond a tape to form an overhanging end portion, one end of each slat being fastened to a tape rung, a telescoping bottom rail, said bottom rail being connected to the other end of the tapes, and lifting cord means extending from the tilting bar to the bottom rail between a tape and an edge of the slat members whereby the head channel, slat members and bottom rail may be adjusted between limits to a range of widths.

7. A Venetian blind of the character described comprising a longitudinally adjustable top channel, a tilting bar mounted in the channel for pivotal movement, said tilting bar having telescoping sections, spaced apart ladder tapes having transverse slat supporting members, at least one tape being suspended from each of the tilting bar sections whereby upon extension of the channel said tilting bar is correspondingly extended reducing the lateral spacing between at least two ladder tapes, a series of horizontal slat members supported on the transverse slat members, each of said slats having two sections, each of said sections reaching between a pair of spaced apart tapes and extending at opposite ends beyond one tape at one slat end and the other slat end fastened to a transverse member of the opposite tape, an adjustable bottom rail connected to the lower ends of the ladder tapes, means connected with the tilting bar for pivoting the bar, and means for raising and lowering the bottom rail and the slat members in sequence.

8. In combination with a Venetian blind having a head channel and a bottom rail, a telescoping tilting bar mounted in said channel and supported for pivotal movement, spaced apart ladder tapes each having transverse members, said tapes being suspended from the tilting bar, a series of vertically spaced apart slat members supported on the ladder tape transverse members, each of said slats being compounded with at least two slat reaches, one portion of each slat reach extending between the spaced apart tapes in overlapping relation, and the other reach of each slat extending beyond a tape to form an overhanging end portion, one end of each tape being fastened to a transverse member concealing the end behind a tape, the bottom rail being suspended by the other end of the tapes, and lifting cord means extending from the tilting bar to the bottom rail between a tape and an edge of the slats whereby the slats may be adjusted between limits to a range of widths.

9. For use in combination with a Venetian blind having a top channel, a tilting bar and a tilting bar mechanism, and means for raising and lowering the blind, a pair of spaced apart ladder tapes having transverse slat supporting members, series of compound slat members supported in vertical spaced relation on the

slat supporting members, each of said slat members having two sections, each of said sections reach at least between the pair of spaced apart tapes and each section extending at one end beyond opposite tapes, and the other slat end fastened to a transverse member of the opposite tape.

10. A Venetian blind comprising, in combination with a top channel box, a tilting bar and tilting bar mechanism supported in the channel box, a bottom rail member, and spaced apart ladder tapes having transverse slat supporting members, a series of horizontal compound slats supported on the ladder tapes, each of the compound slats having two sections, each of said sections overlapping each other only between the spaced apart ladder tapes, one end of each slat section being attached to opposite ladder tapes, and the other end of each slat section extending beyond the opposite ladder tape to which the first slat end is attached.

11. A Venetian blind comprising, in combination with a telescoping tilting bar and tilting mechanism, spaced apart ladder tapes having transverse slat supporting elements, compound slats supported on the transverse slat supporting elements in spaced vertical relationship, each of said compound slats having two sections, each of said sections having an inner and an extending portion, the inner slat portions of each compound slat overlapping between the spaced apart ladder tapes, and the extending portions of each compound slat reaching beyond opposite ladder tapes.

12. For use in combination with an adjustable Venetian blind having a channel box, a tilting bar and tilting mechanism mounted on the channel box, a bottom rail member, and ladder tapes reaching between the tilting bar and the bottom rail, said tapes having slat supporting elements spaced vertically, a compound slat supported on each of the slat supporting elements, said compound slat having two sections, each of said sections having a supported reach extending between said ladder tapes and an overhanging reach extending beyond opposite tapes for each slat.

13. In combination with an adjustable Venetian blind having a channel box, blind tilting means and blind raising and lowering means mounted in the channel box, an adjustable tilting bar provided with telescoping inner and outer sections, spaced apart ladder tapes mounted on the tilting bar for movement in response to the movement of the tilting bar, said ladder tapes having slat supporting elements, compound slats supported on each of the slat supporting elements, each of said compound slats having two sections, each of said sections having a supported reach extending between said ladder tapes and an overhanging reach extending beyond opposite tapes for each slat.

14. In an adjustable Venetian blind, a longitudinally extensible telescoping channel box, a telescoping tilting

bar extensible in response to longitudinal movement of the channel box, ladder tapes extending from the tilting bar in spaced relation and displaceable laterally in response to longitudinal movement of the tilting bar, and a series of compound slats supported on the ladder tapes in vertical spaced relation, said compound slats being formed of two sections, a portion of each section reaching between the ladder tapes forming a double overlapping slat thickness and the other portion of each section projecting beyond the ladder tapes at one end, the other end of each slat section being fastened to a ladder tape whereby upon longitudinal movement of the tilting bar the tapes and compound slats may be aligned accordingly.

15. An adjustable louver enclosure comprising an extensible top channel, an extensible tilting bar pivotally supported to the top channel, two pairs of ladder tape clamping means axially spaced from each other on said tilting bar one of said clamping means of each pair being movable toward each other as the top channel and tilting bar is extended, and away from each other as the channel is contracted longitudinally, the other clamping means being movable in the direction of the channel expansion or contraction, ladder tapes spaced apart and extending from each of said clamping means at one end, said ladder tapes having slat supporting elements, an extensible bottom rail supported at the other end of the tapes, a series of horizontal compound louver slats supported on the slat supporting elements, each of said slats having one end reaching beyond a tape fastened to one end of the other clamping means, and one portion reaching between the pair of tapes fastened to the clamping means movable toward or away from each other as the channel is extended or contracted, the slat reach extending between tapes forming an overlapping portion, each of said slat portions of a single compound slat being fastened adjacent to the other end to a transverse element on the oppositely movable tapes, in overlapping sliding relation, means for pivoting the tilting bar and tape clamping means, and means for raising and lowering the bottom rail and slats.
